UNITED STATES PATENT OFFICE.

WILLIAM DUCHEMIN, OF BOSTON, MASSACHUSETTS.

TENSION DEVICE FOR SEWING-MACHINES.

SPECIFICATION forming part of Letters Patent No. 257,563, dated May 9, 1882.

Application filed February 9, 1882. (No model.)

To all whom it may concern:

Be it known that I, WILLIAM DUCHEMIN, a subject of Her Britannic Majesty, residing at Boston, in the county of Suffolk and State 5 of Massachusetts, have invented a new and Improved Thread-Tension to be Used on Sewing-Machines, of which the following is a specification.

My invention relates to thread-tensions to 10 be used on sewing-machines; and the objects of my improvements are to produce a tension device that can be effectually used whether attached or detached to or from the machine, and of such nature that the largest sized spools 15 can be used therein with the same ease and safety from breakage of thread as the smallest, and that will give out the thread with the same resistance without reference to the finish or uniform size of the thread or spool. These 20 objects I attain by the mechanism shown and illustrated by the accompanying drawings, in which—

Figure 1 is a top view of the mechanism; Fig. 2, a side view; Fig. 3, a vertical section; 25 Fig. 4, a transverse section on line 1, Fig. 3; Fig. 5, a top view of a modification of the device; Fig. 6, a vertical section of the same; Fig. 7, a side view; Fig. 8, a modification of the arm, and Fig. 9 a section of metallic base 30 to which the device is secured when detached from the machine.

Similar letters refer to similar parts throughout the several views, A representing the spool, and t the thread.

The device consists of a straight tube, which, 35 passing through the spool, holds it in a horizontal position, in which it is secured by an upright bar, which is attached to the machine, and a rotating head the shaft of which plays 40 in the tube, and to which are secured side arms provided with loops, which lead the thread to a central exit in the extreme front end of the head, the tension being formed by the action of a transverse spring, which presses against 45 the rotating head, and is constructed as follows:

i a, Fig. 3, represent a straight round shaft, having at its extreme front end a central spiral guide, a', for the exit of the thread, and on 50 which, at a proportionate distance inward, is rigidly secured by means of a boss, d', the cross-arm b b, to the outer ends of which, reaching

inward at right angles therewith, and provided with the loops w and r, are secured the arms c c.

j represents a straight circular tube of such 55 proportion that the shaft a can rotate freely therein, (see i, Fig. 3.) On its front end is secured the shoulder-plate h, on which are projecting lugs e' e', to which is secured by the set-screw e and adjusting-screw f the transverse tension-spring d. The rear end of said tube j fits closely in the central aperture in the block j², which is secured on the top end of the upright post l. When the shaft is placed in the tube j the tension-spring d, being secured 60 in position, as shown at e f, Fig. 2, rests in a groove, x, made for its reception in the boss d', and retains the shaft in position, as shown at d.

To prepare the device for use, the tube j is 65 passed through the central opening in the spool A and into the block j², the inner end of which being conical, the said tube is pressed into said opening and holds the spool rigidly in a horizontal position, in which it is secured by 70 the action of the thumb-screw k. The thread t is then passed through the loops w, r, and a' to the thread-guide of the machine.

In practice as the thread is used by the machine it is drawn from the spool through 75 the loops w and r of the arms c and a' of the head a, and the spool being stationary, the unwinding of the thread causes the head to revolve, when the tension-spring d, pressing 80 against the boss d', causes the necessary friction to produce a tension. If a heavy tension 85 is required, the screw f is turned to the right; if a light, to the left.

The device constructed as described is for 90 large spools, which, being of extra length, require a proportionate length of working-bearing for the shaft i.

Figs. 5, 6, and 7 represent the same device 95 constructed in a different manner, the shaft s being stationary and having on its rear end a thumb-nut, s', and is provided with a rotating head, s⁵, having its working-bearings just in front of a shoulder-plate, s³. At its outer end is a central exit, s⁴, for the thread, and at the inner a cross-arm, n, to the outer ends of which, 100 provided with the loops n² n², are secured the arms n' n', and having the projections g' g', to which, by means of the screws e f, is secured a flat tension-spring, s², which, passing

into the inlet m' in the head s' , (see Fig. 7,) rests in the groove m in the shaft s , (see Fig. 6,) and, pressing against its surface, causes the resistance required to form a tension, and the 5 spring, being the same width as the groove, retains the head in position on the shaft. In principle both devices are the same, the mechanical difference being that in one a stationary spring presses against a rotating shaft 10 and in the other a rotating spring presses 15 against a stationary shaft, and both are prepared and used in the same manner, except that the spool is secured in position by the thumb-nuts s' . The tension-spring may be made of round or flat steel, as may be required, and the loop made for the reception of the adjusting-screw f must be a trifle elongated, as shown at g , Fig. 2.

When either of the devices is intended to 20 be used detached from the machine the upright post l is secured in the metal base D , Fig. 9, and when required for large spools varying in diameter the ends of the arms b will be tubular, as shown at n , Fig. 3, and the arms 25 e so made (see c') that they can be set out or in, as may be required, and held in position by the set-screw n' .

It will be seen that as the thread is drawn 30 through loops much larger than its diameter it is not liable to be influenced by any irregularity of its surface. Consequently the same cannot effect the tension, and, being drawn under yielding pressure from a stationary spool, cannot unwind too freely or become entangled, 35 and whether the spool is large or small the re-

sistance of unwinding will be the same, thus producing a steady and reliable tension without reference to the size of the spool or finish of the thread.

In setting the device on machines, or to be 40 used in connection therewith, care must be taken to lead the thread in a direct line with the shaft a i , as the slightest departure from this rule will destroy the perfect operation of the tension. 45

Having thus described my invention, what I claim as new, and desire to secure by Letters Patent, is—

1. In a tension device for sewing-machines, the transverse tension-spring d , adjusting-screw f , and groove x , arranged and located as and for the purpose described. 50

2. In combination, the revolving shaft a , having a central spiral-formed exit, a' , the cross-bar b b , having the central boss, d' , provided 55 with the groove x , and arms c c ; having the loops w r , the tubular shaft j , having the shoulder-plate h , with the lugs c' c' , the set-screw e , adjusting-screw f , transverse tension-spring d , and block j' , provided with the thumb-screw k 60 and rod l , all arranged and located as and for the purpose set forth. 60

In testimony whereof I have signed my name to this specification, in the presence of two subscribing witnesses, this 7th day of February, 1882. 65

WILLIAM DUCHEMIN.
